UNITED STATES PATENT OFFICE

JAMES M. CUNNINGHAM, OF ENDICOTT, NEW YORK, ASSIGNOR TO THE TABULATING MACHINE COMPANY, OF ENDICOTT, NEW YORK, A CORPORATION OF NEW JERSEY

COMMUTATOR

Application filed August 3, 1928. Serial No. 297,132.

The present invention relates broadly to a new and simple commutator whereby the undesired consequences of sparking are reduced to a minimum.

5 In punched hole accounting machines of the well known Hollerith type in which sensing of the punched holes on a record card is accomplished by electrical means the counters are controlled by circuits established by 10 brushes making a contact with a contact bar or roll. The cards are passed between the brushes and their associated contact and each time a perforation passes beneath a sensing brush it makes a contact with its associated 15 contact member through said perforation. The circuit thus completed is an inductive circuit and as such is liable to cause sparking at these sensing brushes. It has therefore been found advisable to make use of a commutator which is made up of contact segments which are wiped by a brush of a more 20 handy and durable nature than the sensing brushes. This commutator is rotated in synchronism with the feeding of the card so that 25 each index point position of the record card passing under the sensing brushes coincides with the passing of a contact segment of the commutator under its coacting brush. The spacing of these commutator segments 30 are such that the circuit is completed and broken at the commutator and not at the sensing brushes. The sensing brush makes contact through the perforation followed by the completion of the circuit by the commutator 35 and the commutator breaks the circuit before the sensing brush leaves the perforation. In such machines the timing is a vital factor and therefore extreme accuracy must be maintained. To mold insulating material 40 around a skeleton is inaccurate and subsequent machine operations to make such a molded device usable is expensive, furthermore a commutator rotating at a high speed and having comparatively wide insulating 45 segments in proportion to the conducting segments causes considerable wearing on the type of insulating material that may be moulded. It is therefore the purpose of this invention 50 to construct a commutator that may be manufactured accurately at the minimum ex-

pense and of a material that will show the least amount of wear. While in the foregoing description it has been shown how such a commutator relates to record controlled accounting machines it is understood that such 55 a construction could be used whenever a commutator is required.

The main object of the invention consists in the provision of plate glass inserts between the conducting parts of the commutator. 60

Another object of the invention is to provide means to press the non-conducting inserts located between the contact segments in a radial direction against the periphery of 65 the commutator.

A further object of the invention consists in the provision of a housing comprising flange means to assemble the contact segments and the glass plate inserts which later are pressed in a radial direction against 70 said overlapping means of the housing.

Other objects and advantages will be hereinafter set forth in the accompanying specification and claims and shown in the drawings which show by way of illustration what 75 I now consider to be one and a preferred embodiment of the invention.

Fig. 1 is a sectional view of the commutator arranged on a shaft;

Fig. 2 is a sectional view according to line 2—2 of Fig. 1.

Referring to Fig. 1 fixed on a shaft 2 by means of a screw 3 is a sleeve 4 serving as carrier for the commutator assembly. Another sleeve 5 consisting of insulating material is pressed upon sleeve 4 carrying three disk rings 6, 7, and 8 provided around their periphery with transverse flanges 9, 10, 11, and 12. Located between disk rings 6 and 7 85 as well as between disk rings 7 and 8 are cylinders 13, 14 of conducting material as, for example, copper, each having a circumferential line of round spring seats 15 and 16 formed therein each joining a cross-wise 90 groove 17. The dimensions of the spring seats 15 and 16 are proportioned to accommodate pressure springs 18 while the grooves 17 95 accommodate glass inserts 19. Springs 18 press, as may be seen from Figs. 1 and 2, the 100

plate glass inserts 19 against the flanges 9, 10, 11 and 12 of the disk rings 6, 7 and 8, whereby an easily assembled commutator with contact segments alternating with plate glass inserts between said segments is obtained.

Contact cylinders 13 and 14 are connected one with the other by rivets 20 of conducting material thus providing an electrical connection between two brushes sliding on the two commutators. It will be understood, however, that one of the cylinders could be replaced by an ordinary slip ring or that only one cylinder in electrical contact with its supporting shaft could be used.

While there have been shown and described and pointed out the fundamental novel features of the invention as applied to a single modification it will be understood that various omissions and substitutions and changes in the form and details of the device illustrated and in its operation may be made by those skilled in the art without departing from the spirit of the invention. It is the intention, therefore, to be limited only as indicated by the scope of the following claims:

1. A commutator consisting of a plurality of contact segments and a plurality of plate glass inserts between said segments, means for assembling said contact segments and said plate glass inserts and spring means to press the glass inserts in a radial direction against the periphery of the commutator.

2. A commutator consisting of a plurality of contact segments formed on a complex cylinder by intermediate cuts, a plurality of plate glass inserts, means for assembling said contact segments and said plate glass inserts, spring means to press the glass inserts in a radial direction against the periphery of the commutator, said plate glass inserts and spring means being located within said grooves.

3. A commutator consisting of a plurality of contact segments and a plurality of plate glass inserts between said segments, a housing with side walls provided with projecting flanges to assemble said contact segments and plate glass inserts, and spring means to press the plate glass inserts in a radial direction against said flanges.

4. A commutator consisting of a plurality of conducting segments, a plurality of non-conducting inserts between said segments and means to press said inserts in a radial direction against the periphery of the commutator.

5. A commutator consisting of a plurality of contact segments formed on a complex cylinder by intermediate cuts, a plurality of non-conducting inserts between said segments, spring means to press the non-conducting inserts in a radial direction against the periphery of the commutator, said inserts and spring means being located within said cuts.

6. A commutator consisting of a tube, an insulating tube pressed upon said first mentioned tube, a conducting cylinder arranged on said insulating tube and provided with transverse cuts and a circumferential line of spring seats, plate glass inserts located in said cuts and spring means within said seats to press said plate glass inserts in radial directions, and insulating rings assembling said contact cylinder and plate glass inserts by flanges provided on said rings.

In testimony whereof I hereto affix my signature.

J. M. CUNNINGHAM.
